To all whom it may concern:

Be it known that I, Pauline Fracchia, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

The design is characterized by the combination on the dress disclosed, of the multi-striped ribbon trim on the skirt, neckline and front panel, which panel is tucked horizontally, in association with tucked sleeves and an open front skirt, as shown.

I claim:

The ornamental design for a dress, substantially as shown and described.
